UNITED STATES PATENT OFFICE.

FELIX SAMSON, OF NEW YORK, N. Y.

DESIGN FOR NAP-SURFACE OF CLOTHS.

SPECIFICATION forming part of Design No. 12,519, dated October 11, 1881.

Application filed September 2, 1881. Term of patent 7 years.

To all whom it may concern:

Be it known that I, FELIX SAMSON, of New York city, county and State of New York, have originated a novel Design for the Nap-Surface 5 of Cloths, of which the following, in connection with the accompanying drawing, is a full, clear, and exact description.

My present design is of that class on which two patents, Nos. 12,176 and 12,184, were previously issued to me, in which the extreme surface or field of the nap is finished smooth, or nearly so, while figured effects are produced by positive sharp grooves cut into the pile or nap in the act of shearing the same; and my 15 present design consists in a special form and combination of such lines or grooves, by which a novel figured effect is produced, as herein-after set forth.

In the annexed drawing, the figure presents a face view of a piece of cloth finished according to my design, and in which the field or ground of the design consists of plain or smooth finished nap, which nap or ground is indented with two series of lines or grooves, 20 25 *a a* and *b b*, cut into the same in the operation of shearing, so as to divide the ground into stripes of nap standing in relief, and thereby produce a strong figured effect. The lines *a a*, as will be observed, are straight and continuous along the cloth, and are disposed at wide intervals apart, and between them are arranged the lines *b b*, which are alternately straight and sinuous or wavy throughout their 30 course, so that thus, while the general trend of the several lines is similar, yet sufficient diversity is introduced by the waved portions of the straight lines *b b* as to enliven the design without being too monotonous on one hand or

too striking on the other, thereby producing a novel and pleasing effect. 40

I prefer to use two of the lines *a a* in a single stripe, and three of the lines *b b* in one stripe; but the specified number of lines is not essential to the effect of my design.

I also prefer, as will be observed from the drawing, to have the wavy portions of the lines *b b* in one stripe to alternate in position with the straight portions of the same lines *b b* in the next stripe, as this arrangement obviously gives greater diversity and liveliness to the design and renders its effect much more ornate. 45 50

I have described the design as being produced by cutting grooves into the nap, as this is much preferable; but it is obvious that the design is not limited to this mode of production. 55

What I claim is—

1. The specified design for the nap-surface of cloth, consisting of stripes of continuous straight lines alternating with parallel stripes of lines alternately straight and waved throughout their course, substantially as herein illustrated. 60

2. The illustrated design for the nap-surface of cloths, consisting of stripes of continuous straight lines alternating with parallel stripes of lines alternately straight and wavy in their course, and so disposed that the wavy portion of the lines in one of said stripes alternates with the straight portion of the similar lines in the next stripe, substantially as herein specified. 65 70

FELIX SAMSON.
